UNITED STATES PATENT OFFICE.

CHARLES RUBY MOORE, OF MAPLEWOOD, NEW JERSEY, AND JOHN M. HAYWARD, OF NEW YORK, N. Y., ASSIGNORS TO WESTERN ELECTRIC COMPANY, INCORPORATED, OF NEW YORK, N. Y., A CORPORATION OF NEW YORK.

DOUBLE DIAPHRAGM TRANSMITTER.

Application filed July 30, 1924. Serial No. 729,010.

This invention relates to telephone equipment and particularly to linemen's telephone instruments.

Heretofore such equipment has consisted of a handset, that is to say an instrument wherein the transmitter and receiver are mounted on a common handle. In using such a handset while talking, the lineman has to use one of his hands to hold the handset. Therefore, he has only one hand free for testing, etc.

The object of the present invention is to provide a light weight transmitter for linemen to fasten on the coat or other piece of clothing and when used with a headset will replace the customary handset which must be held in the hand, leaving only one hand free for testing, etc.

In accordance with this invention, a rugged transmitter is provided which will withstand the hard usage such instruments get in service, and which at the same time is sensitive and light in weight, so that it may be attached by a clip to the lineman's coat or other piece of clothing and in that position will take up the sound of his voice very readily, the lineman being provided with an ordinary head receiver for listening.

More particularly the transmitter consists of a casing of very light material, for example, aluminum, formed of preferably two symmetrical parts which carry a multiple diaphragm carbon button, and when joined and fastened together provide a housing for the transmitter button with air passages leading from the open end of the casing to the diaphragms, and make up a symmetrical exterior contour.

Other features of the invention and advantages will appear from the following description and by the appended claim, reference being had to the accompanying drawing in which Fig. 1 is an enlarged sectional view of the transmitter taken approximately on line 1-1 of the Fig. 3. Fig. 2 is a side view of the transmitter with the casing partially cut away and Fig. 3 is a top view of the transmitter showing the protecting grid on the front portion of the mouthpiece.

Similar reference characters refer to similar parts throughout the description.

The telephone transmitter of this inven-

tion consists of a mouthpiece which is preferably formed by two similarly shaped parts 55 10 and 11 fastened together by means of screws 12 shown in Figs. 1 and 2. The parts 10 and 11 are each provided with a semi-shell shaped portion 13 and 14 which are preferably made integral with their respective parts 10 and 11 and adapted to register to form a housing for a transmitter button T. The shells 13 and 14 are each provided with an aperture or air passage 15 and 16 disposed coaxially and adapted to 60 receive the hubs of their respectively associated discs 17 and 18 provided for insulating the transmitter button from the mouthpiece parts 10 and 11, respectively.

The transmitter button T consists of two 70 electrodes 19 and 20 which are fastened together by means of a shoulder ring 21 screwed on electrode 19. An insulating disc 23, disposed between the shoulder portion 22 of ring 21 and electrode 20 is provided 75 for insulating the electrodes from each other. An insulating disc or barrier 24 interposed between electrodes 19 and 20, is provided for insulating the electrodes and to form a path across which the current must pass. 80

Each electrode, 19 and 20, is associated with a conical shaped diaphragm 25 and 26 which have their apexes disposed in juxtaposition and each in contact with the carbon granules as shown in Fig. 1. On opposite 85 sides of each diaphragm, there are provided a plurality of damping paper discs 27 generally known as "book damping". The screens 36 and 37 are provided for protecting the diaphragms 25 and 26 from dust 90 particles which may fall into the air passages in the shells 13 and 14. The screens 36, 37 the diaphragms 25 and 26, together with the paper discs 27 are held in adjusted position by means of flanges 28 and 29, 95 which are screwed in the electrodes 19 and 20 respectively. The flanges 28 and 29 are each provided with a hub portion adapted to fit into their respectively associated apertures in the insulating discs 17 and 18 and 100 cooperate therewith for holding the transmitter button and the spring rings 30 and 31 in position.

The spring rings 30 and 31 are disposed between electrodes 19 and 20 and the insulating discs 17 and 18. These rings are pro- 105

vided for holding the transmitter button against movement in the housing and to protect the button from the usual accidental shocks and jars while in use. The rings 30 and 31 are each provided with a lug 32 and 33 upon which the wire terminals 34 and 35 may be attached in any convenient manner. A protecting screen 38 is mounted on the front portion of the transmitter mouthpiece and is held securely thereon by means of screws 40. On one side of the mouthpiece there is mounted a pair of pincers 39 shown in Figs. 2 and 3 which are adapted for securing the transmitter to the belt or coat of the lineman. The transmitter of this invention is also well adapted for use with deaf sets or wherever a very sensitive transmitter is required.

What is claimed is:

A telephone transmitter comprising a 20 mouthpiece formed by the registry of two substantially identical shaped parts, said parts having walls forming a housing, a plurality of air passages formed by said walls and the mouthpiece, a microphone, a 25 pair of insulating apertured discs for supporting the microphone in said housing, and conducting spring discs interposed between the microphone and the insulating discs for holding the microphone against lateral 20 movement in said housing and for securing the conducting wires of said transmitter.

In witness whereof, we hereunto subscribe our names this 22 day of July, A. D. 1924.

CHARLES R. MOORE.
JOHN M. HAYWARD.
